UNITED STATES PATENT OFFICE

122,836

DESIGN FOR A COMBINED LAMP AND RADIO RECEIVING SET

Daniel J. Crowley, Grosse Pointe, Mich.

Application April 22, 1940, Serial No. 91,871

Term of patent 14 years

To all whom it may concern:

Be it known that I, Daniel J. Crowley, a citizen of the United States of America, residing at Grosse Pointe, in the county of Wayne and State of Michigan, have invented a certain new, original, and ornamental Design for a Combined Lamp and Radio Receiving Set, of which the following is a specification, reference being had therein to the accompanying drawing, forming a part thereof, wherein Figure 1 is a perspective view of my new design of a combined lamp and radio receiving set; Figure 2 is a sectional view showing the profile of the intermediate portion of the lamp; and Figure 3 is a sectional view taken sub-

stantially on the plane indicated by the line 3—3 of Figure 1.

The design of combined lamp and radio receiving set is substantially symmetrical about its vertical axis in that the side of the set opposite to the side shown in the drawing is the same in appearance, with the exception that the indicia on the reverse side varies to indicate the different radio receiving stations.

I claim:

The ornamental design for a combined lamp and radio receiving set substantially as shown and described.

DANIEL J. CROWLEY.
